[57] CLAIM

The ornamental design for a handheld two way radio, as shown and described.

DESCRIPTION

FIG. 1 is a front perspective view of a handheld two way radio showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken line showings throughout the views are for illustrative purposes only and form no part of the claimed design. The surfaces obscured by the broken lines are continuous throughout.
